UNITED STATES PATENT OFFICE.

WILLIAM A. MCCOLLOUGH, OF WEBSTER CITY, IOWA.

FEEDING-TROUGH.

1,175,650.

Specification of Letters Patent. Patented Mar. 14, 1916.

Application filed February 23, 1915. Serial No. 9,887.

To all whom it may concern:

Be it known that I, WILLIAM MCCOLLOUGH, citizen of the United States of America, and resident of Webster City, 5 Hamilton county, Iowa, have invented a new and useful Feeding-Trough, of which the following is a specification.

The object of this invention is to provide an improved construction for feeding 10 troughs.

A further object of this invention is to provide an improved construction for feeding troughs designed especially for feeding alfalfa and the like to hogs, sheep, and so 15 forth.

A further object of this invention is to provide an improved construction for a feeding trough having a base and a trough and a rack hinged to opposite sides thereof 20 and adapted to rest in superposed relations in use, and to be swung in opposite directions for emptying and cleaning.

My invention consists in the construction, arrangement and combination of elements 25 hereinafter set forth, pointed out in my claims and illustrated by the accompanying drawing, in which—

Figure 1 is a side elevation of the device in position for use, a portion of the trough 30 being broken away. Fig. 2 is an end elevation of the device showing the trough and rack swung to open or cleaning position, a portion of the hopper being broken away.

In the construction of the device as 35 shown a base member is formed of longitudinal frame members 10 spaced apart and connected by cross members 11, in this instance three in number. The frame members 10, 11 preferably are formed of metal 40 straps suitably riveted together. Trough supports 12 are laid upon and riveted in their central portions to each of the cross members 11, and said trough supports are curved upwardly at their ends, to conform 45 to the curvature of the trough to be supported therein. The trough supports 12 are bent at their ends to form eyes or hinge members 13, 14. A trough is provided and is formed of a sheet metal body 15 provided 50 with metal cleats 16 therebeneath. The cleats 16 are formed with integral eyes 17 or hinge members at one end, and are pivotally connected to the eyes 13 by hinge bolts 18. Thus the trough is hinged to the base 55 member and is adapted at times to rest on the supports 12 as shown in Fig. 1, and at

times to be swung upwardly and outwardly therefrom as shown in Fig. 2.

A rack is provided and is formed of a sheet metal hopper 19 open at top and bottom and a skeleton frame or rack 20 connected to and projecting below the lower part thereof. The skeleton frame or rack 20 is constructed of yoke-shaped bars 21 connected at their ends to the lower portion 65 of the hopper 19, and a longitudinal member 22 riveted to the median line of the closed portions of and connecting said yoke-shaped members, together with spaced end bars 23 connecting said hopper and the 70 bases of the end yoke members. Transverse supporting bars 24, preferably of angle iron, are connected to the skeleton frame 20, and said transverse supporting bars are formed at one end with eyes 25 or hinge 75 members connected by hinge bolts 26 to the eyes 14. The transverse supporting bars preferably are spaced above the lower portion of the skeleton frame 20 so that said skeleton frame projects downwardly within 80 the trough when the device is in position for use. Thus the feeding rack is pivotally connected to the base member, and in use is adapted to be supported on the trough, the free ends of the transverse supporting bars 85 resting on the free margin of the trough as shown in Fig. 1, and to be swung laterally at times as shown in Fig. 2.

Inclined braces 27 are provided between the ends of the cross base members 11 and 90 the upper ends of the trough supports 12, and inclined braces 28 are provided between the ends of the transverse supports and the skeleton frame 20.

A loop handle 29 preferably is secured to 95 the free margin of the trough for ease in handling the same and swinging it to either position. A yoke-shaped latch 30 is pivoted to the opposite margin of the trough and is adapted to engage a notch 31 in the free 100 end of one of the transverse supports 24, to prevent accidental displacement of the feed rack from the trough.

This device is especially designed for 105 feeding alfalfa hay or the like to small animals such as hogs, without waste, and one of its great advantages is that it is perfectly sanitary. The hay is placed in the hopper, when the device is positioned as in Fig. 1, and is secured by the animals 110 through the skeleton frame beneath the hopper. The trough receives small particles

which fall from the rack, whence such particles may be reached by the feeding animals. When the feeding period is ended, and it is desired to empty and clean the 5 trough, and prevent the animals from getting therein, the rack and then the trough are swung to inverted position as shown in Fig. 2. To place in position for use the trough is first moved to upright position, 10 and then the rack is swung to position thereon.

I claim as my invention—

1. A device of the class described, comprising a base, a trough hinged to one side 15 of said base and adapted to rest thereon, and a rack hinged to the opposite side of said base and adapted to rest on said trough, said rack comprising a hopper and a skeleton frame therebeneath, said skeleton frame 20 projecting within said trough when the members are positioned for use.

2. A device of the class described, comprising a base, a trough fitted and hinged to one side of said base, and a feed containing 25 rack composed of a hopper and a skeleton frame therebeneath, said skeleton frame being formed intermediate of its top and bottom with transverse supports hinged to the opposite side of said base, the free ends of said transverse supports being adapted to 30 rest on the hinged margin of the trough when the device is in position for use, said skeleton frame being shorter and narrower at its bottom than the top of said trough and extending therewithin.

Signed by me at Webster City, Iowa, this 35
29th day of January, 1915.

WILLIAM A. MCCOLLOUGH.
